UNITED STATES PATENT OFFICE.

MIKE F. RETTMAN, OF KIMBERLY, WISCONSIN.

DOOR HOLDER.

Application filed January 20, 1926. Serial No. 82,505.

This invention relates generally to doors, and has more particular reference to a means for maintaining a swinging door, such as those employed in garages and the like, in an open position in order that the vehicle may be driven into the garage or out of the same without coming in contact with the door which is usually the case when no means is provided for maintaining the door in an entirely open position.

The primary object of the present invention is to provide such a holder that it is of relatively simple construction that may be applied to all horizontally swinging doors in a simple and inexpensive manner.

A further object is to provide means within easy reach for releasing the door in order that it may be moved to closed position.

Other objects will become apparent as the nature of the invention will be better understood by reference to the accompanying drawing and following specification.

In the drawing wherein like reference characters indicate corresponding parts throughout both of the views:

Figure 1 is a fragmentary horizontal section taken through a garage equipped with a horizontally swinging door provided with a holder constructed in accordance with the present invention, the door being shown in open position, and

Figure 2 is a fragmentary front elevation of the garage, also showing the door in open position and maintained in such position through the medium of my improved invention which is disclosed in edge elevation.

Now having particular reference to the drawing, 5 indicates fragmentarily a garage or other building that is provided with a horizontally swinging door 6.

My invention constitutes the provision of an angle bracket 7 that is adapted to be secured to the inner side of the door 6 adjacent its upper edge, and to the horizontal portion of which is pivotally connected as at 8, a relatively elongated arm 9 that is provided throughout practically its entire length with a slot 10, through which is adapted to extend a pin 11 which depends from the top of the door casing slightly within the door opening thereof. The pin 11 is formed intermediate its end with an opening for receiving a locking cotter pin 12 for obviously preventing the disengagement of the arm 9 with respect thereto.

My door holder further constitutes the

provision of a relatively elongated lever 13 formed at its inner edge and intermediate its ends with an ear 14 that is pivotally secured to the under side of the arm 9 adjacent the outer edge thereof as more clearly shown in Figure 1. Pivotally attached to said lever adjacent its forward end is a bolt 14 that extends inwardly toward the arm 9 and is normally engaged over the slot 10 of said arm, the same being slidably guided through medium of a bracket 16 secured to the under side of the arm directly in back of the forward end of said slot 10.

The bolt 14, the free edge of which is beveled as shown, is normally maintained in a position across the slot 10 through medium of a retractile coil spring 17, interconnecting the lever 13 and arm 10 at their forward ends.

It will thus be seen that when the door 6 is in closed position, the pin 11 will be positioned through the slot 10 adjacent the pivotal end of the arm 9. When the door 6 is moved to open position, the arm 9 will be pulled outwardly by the door and slide upon the pin 11. Such action will cause the pin to pass beyond the bolt 14 and prevent the closing of the door by reason of the fact that said pin 11 will engage the unbeveled edge of the bolt in an obvious manner.

In order that the door may be closed, there is secured to the inner end of the lever 13, a cord 18 that extends laterally therefrom and is guided through the eye of an eye bolt 19 upon the inner side of the door 6 and then extends downwardly in order that a pull upon the same will swing the lever upon the pivot for retracting the bolt 14 in the guide bracket 16 for obviously moving the same away from the slot 10, allowing the arm 9 to be moved inwardly upon the pin 11.

Said bolt and lever will be returned to their normal position as shown in Figure 1 through provision of the spring 17.

It will be obvious that I have provided a highly novel, simple, and efficient form of door holder for maintaining the swinging door in its open position to permit the entrance or exit of vehicles with respect to the building with which said door is associated.

Minor changes may be made in the invention without departing from the spirit and scope of the appended claims.

Having thus described the invention,

what I claim as new and desire to secure by Letters Patent is:

1. In a door holder of the class described, a slotted arm pivotally secured at one end to the inner side of a swinging door adjacent the upper edge thereof, a pin projecting downwardly from the top of the door casing into the door opening, said pin being operable within said slot, a lever pivoted intermediate its end to the intermediate portion of said arm, a bolt mounted on the forward end of said lever and extending across the forward end portion of said arm and adapted to engage said pin for securing the arm against sliding movement whereby the door is held in an open position, and means for actuating the lever to release the sliding bolt from engagement with said pin whereby the arm may be free to slide along the pin to permit the door to be closed.
2. In a door holder of the class described, a slotted arm pivotally secured at one end to the inner side of a swinging door adjacent the upper edge thereof, a pin projecting downwardly from the top of the door casing into the door opening, said pin being operable within said slot, a lever pivoted intermediate its ends to the intermediate portion of said arm, a bolt mounted on the forward end of said lever and extending across the forward end portion of said arm and adapted to engage said pin for securing the arm against sliding movement whereby the door is held in an open position, and means for

actuating the lever to release the sliding bolt 35 from engagement with said pin whereby the arm may be free to slide along the pin to permit the door to be closed, said means comprising a cable attached to the inner end of the lever.

3. In a door holder of the class described, a slotted arm pivotally secured at its inner end to the inner side of a horizontally swinging door adjacent the upper edge thereof, a pin projecting downwardly from the top of the door casing into the door opening, said pin projecting downwardly through the slot in said arm, a lever pivotally supported intermediate its ends to the intermediate portion of said arm, a bolt secured to the forward end of said lever and extending across the forward portion of said arm, guide means for the free end portion of said bolt arranged on said arm, resilient means connecting the forward end of the arm and lever respectively for holding the bolt in engagement with said pin whereby the arm is secured against sliding movement to maintain the door in an open position, and means associated with the inner 60 end of the lever for actuating the same to release the bolt from engagement with said pin whereby the arm is free to slide along the pin to permit the door to be moved to a closed position.

In testimony whereof I affix my signature.

MIKE F. RETTMAN.
